UNITED STATES PATENT OFFICE.

JOHN M. FEDDERS, OF BUFFALO, NEW YORK, ASSIGNOR TO FEDDERS MANUFACTURING COMPANY, INC., OF BUFFALO, NEW YORK, A CORPORATION OF NEW YORK.

RADIATOR.

1,263,397.

Specification of Letters Patent. Patented Apr. 23, 1918.

Application filed September 2, 1916. Serial No. 118,246.

To all whom it may concern:

Be it known that I, JOHN M. FEDDERS, a citizen of the United States, residing at Buffalo, in the county of Erie and State of New York, have invented new and useful Improvements in Radiators, of which the following is a specification.

This invention relates to a radiator which is more particularly designed for use on 10 motor trucks which are operated by explosion engines but the same is also applicable to other uses.

The objects of this invention are to provide a radiator for this purpose which is 15 comparatively simple and durable in construction and efficient in operation, which can be produced at low cost, which is not liable to get out of order when subjected to severe usage and which furnishes the maximum efficiency for the amount of metal incorporated in the same.

In the accompanying drawings:

Figure 1 is a front elevation, partly in section, of a radiator embodying my improvements. Fig. 2 is a horizontal section of the same taken on line 2—2, Fig. 1. Fig. 3 is a vertical longitudinal section taken on line 3—3, Fig. 1. Figs. 4 and 5 are detached perspective views of the two sections of a 30 water tube of the radiator. Fig. 6 is a fragmentary vertical section showing a modification of the means for detachably connecting the body and perforated head of one of the water boxes.

Similar characters of reference indicate corresponding parts throughout the several views.

In its general organization this radiator comprises water boxes or headers 1, 2 preferably of sheet metal which may be arranged one above the other, as shown in the drawings, or in any other suitable relation, so that one of the water boxes, for instance the upper one 1, may serve as the inlet chamber 40 or compartment for the water to be cooled, and the lower one 2 as the outlet chamber 45 from which the cooled water is returned to the cooling or circulating system of the explosion engine.

Arranged between these two water boxes are a plurality of upright water tubes or conduits 3 preferably of sheet metal which communicate at their opposite ends with these water boxes so that the water is conducted from the inlet box 1 to the outlet box

2 and is thus cooled or lowered in temperature while being transferred from one water box to the other owing to the radiation of the heat of the water to the external air which is in contact with the outer surface of 60 said tubes.

The upper water box preferably comprises an upper body 4 which is provided at its lower edge with a marginal flange 5, and a lower head 6 which is detachably connected 65 at its margin with the flange of the companion body. Leakage between the lower head and the flange of the upper body is prevented by interposing a gasket or packing 7 between the margins of these parts, as 70 shown in Figs. 1 and 3.

The lower water box or header comprises a lower body 8 having its upper edge provided with an external flange 9, and a head 10 which is detachably connected at its marginal portion with said flange, a packing or gasket 11 being interposed between the margins of the head 10 and said flange 9 for preventing leakage. 75

Any suitable means may be employed for connecting the head and body of each water box but the means which are preferred for this purpose are so designed that they also connect the two water boxes with each other, thereby materially stiffening and strengthening the structure as a whole. In their preferred form these means comprise a plurality of tie rods 12 each of which has its opposite ends provided with external screw threads and arranged in corresponding openings in 80 the heads and body flanges of both water boxes, inner screw nuts 13 arranged on each of said tie rods and engaging with said heads, and outer screw nuts 14 arranged on each of said tie rods and engaging with the 85 body flanges of the water boxes.

If desired, however, the head and body flanges of each water box may be connected with each other independently of the other water box in which case this connection may 100 be effected by short bolts 12^a, as shown in Fig. 6.

Each of the tubes arranged between the water boxes preferably comprises two like sections each of which has a semi-cylindrical body composed of a plurality of short semi-cylindrical tube or body portions 15 which are arranged end to end in a longitudinal row, two longitudinal flanges arranged on opposite sides of each tube sec- 110

tion and each flange composed of a plurality of short portions 16 which are arranged end to end on the same side of the tube but are connected at their inner longitudinal edges 5 with the longitudinal edges of the companion semi-cylindrical tube portions and a plurality of radiating fins or wings arranged in a longitudinal row on the outer side of a respective tube section. Each of these radiating fins or wings is arranged crosswise of the respective tube section and preferably formed integrally therewith by folding or doubling the sheet metal from which the tube sections are made at intervals so as to 10 form a succession of plaits which alternate with the rows of tube portions and flange portions. Each of these plaits has two plies 15 17, 17 the outer edges of which are connected with each other while their inner edges 20 are connected with the opposing transverse edges of the adjacent tube and flange portions of one of the tube sections.

The central part of each radiating fin or wing has its outer edge curved concentrically or substantially so relatively to the axis of the tube in its completed form, as shown at 18 and the opposite end portions 19 of each wing or fin have their outer edges arranged parallel or substantially so with 25 the adjacent flange portions of the tube, or 30 in other words, parallel to a line drawn diametrically through the axis of the tube.

Two tube sections of this character are placed with the concave sides of their body 35 portions facing each other and their flange portions in engagement and then the latter are preferably connected by soldering to complete the tube and avoid leakage. If desired the connection between the flange portions of two tube sections may be otherwise 40 effected.

The heads 6, 10 of both water boxes are provided with a plurality of corresponding openings which receive opposite ends of the 45 water tubes, each of these openings being constructed to form a central circular portion 20 and straight or slotted portions 21, 21 arranged on diametrically opposite sides of the central circular portion, so as to correspond in shape to the cross section of two 50 tube portions and the adjacent flanges of a water tube which is designed to fit into this opening of a water box head.

The joints between the water tubes and 55 water box heads are preferably made water

tight by solder although this may be accomplished in any other suitable manner.

In the manufacture of radiators these water tubes are preferably arranged in rows crosswise of the radiator, the number of rows 60 depending upon the desired capacity of the radiator. When a plurality of rows of tubes are employed the disposition of the tubes in the several rows is such that they are staggered in a direction fore and aft of the 65 radiator, whereby each tube in one transverse row will be arranged lengthwise in line with the space between two tubes in an adjacent row, thereby causing the air when passing from the front side to the rear side 70 of the radiator to take a tortuous course instead of an unobstructed path, thus increasing the efficiency of the radiator.

The tube sections of this radiator can be produced expeditiously and economically 75 by simple operations and the assembly of the same with the water boxes can also be effected quickly so that the radiator as a whole can be produced at low cost. Furthermore, the construction of the radiator is such that 80 the same is strong and durable and not liable to leak or get out of order when subjected to undue strains, and if any repairs on the same are necessary it is possible to conveniently dismember and re-assemble the various 85 parts of the radiator for this purpose without involving undue expense.

I claim as my invention:

A tube for radiators comprising two sections each of which has a longitudinal row 90 of semi-cylindrical body portions, longitudinal flange portions arranged at opposite edges of each body portion, and radiating fins or wings arranged on the outer sides 95 of said body portions and flange portions, each fin being constructed in the form of a plait having two plies the outer edges of which are connected with each other while their inner edges are connected respectively with the adjacent opposing edges of adjacent semi-cylindrical body portions and adjacent flange portions, the outer edge of each fin having its central part curved concentrically with the axis of the tube while the 100 end portions of each fin have their outer edges parallel with the inner edges and the two sections of the tube have their flanges connected with each other.

JOHN M. FEDDERS.
